AUTOMOBILE TAIL LAMP ASSEMBLY

Clifford S. Voss, Clawson, Mich., assignor to Chrysler Corporation, Highland Park, Mich., a corporation of Delaware

Application July 26, 1955, Serial No. 37,128

Term of patent 7 years

(Cl. D48—32)

Fig. 1 is a side elevational view of an automobile tail lamp assembly showing my new design;

Fig. 2 is a front elevational view thereof;

Fig. 3 is a top plan view of the automobile tail lamp assembly;

Figs. 4, 5, 6, 7, 8, and 9 are sectional views taken on the lines 4—4, 5—5, 6—6, 7—7, 8—8 and 9—9, respectively, of Fig. 1.

I claim:

The ornamental design for an automobile tail lamp assembly, substantially as shown.
